COSMETIC CABINET

Walter P. Koeller, Chicago, Ill.

Application July 28, 1938, Serial No. 221,786

19 Claims. (Cl. 132—79)

This invention relates to a combined cosmetic cabinet and illuminated mirror.

It is an object of this invention to provide a combined cosmetic cabinet and illuminated mirror which is relatively simple and inexpensive from the manufacturing standpoint, compact, rugged and durable in construction and pleasing in appearance.

A further object is to provide a cabinet specifically for receiving cosmetics, having an article receiving drawer and an internal article receiving shelf in which means are provided for manipulating the shelf in response to the opening of the drawer to project the articles thereon at least partially beyond the walls of the cabinet so that they may be placed in a position readily available for use or removal and replacement.

Another object is to provide a cabinet of the character stated, having a closure panel and an internal article receiving shelf in which means are provided for simultaneously manipulating the closure panel and the shelf to project the articles on the shelf at least partially beyond the walls of the cabinet so that they may be placed in a position readily available for use or removal and replacement.

Another object is to provide a cabinet of the character stated having an article receiving drawer, a closure panel and an internal article receiving shelf in which means are provided for manipulating the closure panel in response to the opening and closing of the drawer so that articles on the shelf and in the drawer may be simultaneously made available for use.

Another object resides in the provision of a cabinet having an article receiving drawer, an internal article receiving shelf and a lid overlying said shelf in which means are provided for manipulating the shelf and lid in response to the opening of the drawer to project the articles on the shelf at least partially beyond the walls of the cabinet so that they may be placed in a position readily available for use or removal and replacement.

A further object is to provide a combined cosmetic cabinet and illuminated mirror in which the cabinet is provided with an article receiving drawer arranged to control the energization of the means employed for illuminating the mirror.

Applicant's invention further contemplates the provision of a compact "make-up" cabinet having as a part thereof a mirror and means behind the mirror for indirectly illuminating the face of the user seated in front of the cabinet and for illuminating the mirror substantially solely by

means of light reflected from the face of the user so seated.

A further object of applicant's invention is to provide a combined "make-up" cabinet and illuminated mirror of the above stated character in which means are provided for controlling the illuminating means in response to the opening and closing of the cabinet.

Other and further objects and advantages of the invention will be apparent from the following description when taken in connection with the accompanying drawings, wherein:

Fig. 1 is a view in perspective of a combined cosmetic cabinet and "make-up" mirror constructed in accordance with the present invention;

Fig. 2 is a view in perspective of the cabinet of Fig. 1, with the drawer, lid and article receiving shelf in open position, and the "make-up" mirror removed for purposes of illustration;

Fig. 3 is a view in perspective of the rear of the "make-up" mirror;

Fig. 4 is a vertical section taken substantially along the line 4—4 of Fig. 1;

Fig. 5 is a vertical section taken along the line 5—5 of Fig. 2;

Fig. 6 is a fragmentary vertical section taken along the line 6—6 of Fig. 4;

Fig. 7 is a vertical section taken along the line 7—7 of Fig. 4;

Fig. 8 is a plan section along the line 8—8 of Fig. 4;

Fig. 9 is a fragmentary plan section along the line 9—9 of Fig. 2;

Fig. 10 is a fragmentary section along the line 10—10 of Fig. 7;

Fig. 11 is a fragmentary vertical section along the line 11—11 of Fig. 10; and

Fig. 12 is a fragmentary detail sectional view along the line 12—12 of Fig. 2.

As shown in the drawings for illustrative purposes, a cosmetic cabinet constructed in accordance with the invention comprises a sheet metal stamping 2, Fig. 7, bent or otherwise formed to provide a base 4 and opposite side walls 6 and 8. A stamped sheet metal plate or panel is secured, as by welding or otherwise, to the base 4 and the side walls 6 and 8, to form a rear wall 10. The forward edges of the side walls 6 and 8 are inclined, preferably at an angle of substantially forty-five (45) degrees, and to these inclined edges is secured a stamped sheet metal plate 12 having inwardly bent flanges 14 welded or otherwise secured to the side walls 6 and 8, the plate 12 forming a front panel of the cabinet.

The base 4 is provided with spaced supporting 55

feet 16 which may be formed by striking out or depressing portions of the base, or by cementing or otherwise securing suitably shaped pieces of cushioning material to said base.

5 A sheet metal stamping 18 is bent or otherwise formed to provide a drawer 20 having a base 22 and side walls 24 and 26. The drawer 20 is slidably supported upon the base 4 of the cabinet by noiseless guides and tracks 28 and 30. The guides 28 preferably comprise substantially C shaped metal channels snugly receiving the outwardly turned flanges 32 of the channel shaped tracks 30 supported on the base 4 by the trough shaped sheet metal angle irons 34, welded or otherwise fastened to the base 4. The guides 28 are similarly secured, preferably by spot welding, to the bottom 22 of the drawer.

A lid or closure means 36 comprises a sheet metal plate or panel 38 hingedly connected as at 40 to the top of the rear panel or wall 10, and chromium plated on its lower surface to provide a mirror-like reflecting surface.

The face panel 12 is provided with a central opening to receive a semispherical or parabolic reflector 42, to the rim of which are spot welded or otherwise fastened angularly spaced and radially extending arms or rods 44 which are preferably chromium plated. To the inner ends of these arms 44 is secured a ring or annulus 46 for detachably receiving and supporting a sheet metal ring 48 secured or formed integrally with an annulus 50 having an inwardly turned peripheral rim 52 for clampingly receiving the rim of a disk-like "make-up" mirror 54. The outer 35 ends of the rods 44 have threaded apertures to receive a screw 45 which attaches to the reflector 42 an angle plate 47 which engages the under surface of the front panel 136, thereby providing means to position the reflector 42 into the front panel.

40 The bottom of the reflector 42 is extended axially thereof to receive a socket 56 for receiving a lamp or other electrically operated luminous means 58. It should be noted that the "make-up" mirror 54 is smaller in diameter than the rim of the reflector 42 and accordingly rays of light from the luminous means 58 will be directed by the reflector 42 about the periphery of the mirror into the face of a user seated before the cabinet. 45 The consequent indirect illumination of the mirror solely by the rays of light reflected from the face of the user eliminates shadows and provides in the mirror a sharp and clear image so that cosmetics may be applied evenly and skillfully to obtain the desired effect.

The cabinet is provided with a shelf 60 comprising a sheet metal plate 62 having a plurality of spaced apertures to receive bottles or jars 64, such as a bottle of astringent, a jar of cleansing 60 cream, and a bottle of powder base. Sheet metal straps 66, substantially U shaped in configuration, are provided with outwardly bent flanges 68 spot welded to the shelf 62, the straps 66 supporting the articles inserted in the openings in 65 the plate 62. The plate 62 of the shelf 60 is formed with depending front and rear flanges 70 for strengthening purposes and to provide a skirt which, when the shelf is in raised position, as shown in Fig. 2, acts as a screen hiding from 70 view the parts in the interior of the cabinet.

The shelf 60 is mounted for vertical reciprocity upon channel shaped angle irons 72 by L shaped brackets 74 riveted to the plate 62 and spot welded or otherwise secured to the angle irons 72.

75 The angle irons 72 are provided with outwardly

extending flanges 76 snugly received within C shaped guide bars 78 spot welded or otherwise secured to the side walls 6 and 8. The closure means or lid 36 is connected to the angle irons 72 for vertical swinging movement simultaneously with the vertical reciprocity of the shelf 60, by means of links 80. Each of the links 80 is pivotally connected at one end, as by a pin 82, to the bracket 74 and at its other end is detachably connected by a pivot pin 84 and a clamping spring or resilient strip 86 to the lug 88 of a bracket 90 pivoted or otherwise secured to the plate 38 of the closure means 36. The angle irons or operating members 72 are vertically reciprocated in response to the opening and closing of the drawer 20. For this purpose the side walls 24 and 26 of the drawer 20 are formed to provide laterally directed flanges, each of which comprises a portion 92 substantially parallel to the base 22 of the drawer and parallel to the path of movement of the drawer, and an inclined portion 94, the under surface of the portions 92 and 94 forming a cam surface adapted to be engaged by a cam roller 96 secured to the forward end of a lever 98. Each lever 98 is pivoted at an intermediate point by a pin 100 to a lug 102 formed on or secured to a side wall of the cabinet. The rear ends of the links 98 are provided with arcuate slots 104 to receive pins 106 secured to the lower ends of the operating members 72. It will be seen that as the drawer 20 is moved from closed to open position, the inclined portions 94 will cause the levers 98 to be swung in a clockwise direction from the position shown in Fig. 4 to the position shown in Fig. 5, thereby raising the shelf 60 and swinging the lid or closure means 36 to its open position. The horizontal flange portions 92 prevent reverse movement or oscillation of the levers 98 and hence retain the shelf and lid in open position, as shown in Fig. 5. During the closing movement of the drawer, and when the cam roller 96 engages the inclined flange portions 94, the weight of the shelf 60, the lid 36 and the weight of the articles on the shelf 60 will through the levers 98 and the cam roller 96 move the drawer into fully closed position.

The drawer 20 comprises, in addition to the stamping 18, a sheet metal plate or front panel 108 riveted or otherwise secured to the depending flange 110 of the stamping 18 and by angle irons 112 to the side walls 24 and 26 of the drawer. A plate 114, substantially V shaped in cross section, is mounted within the drawer 20, to which it is secured by welding or otherwise fastening flanges 116 and 118 to the front plate 108 and the bottom 22. The rear, upwardly extending portion 120 of the plate 114 is provided with a plurality of openings 122 to receive and position upon the bottom 22 a set of jars or other containers, such as a box of face powder and jars of face creams. The forward downwardly extending portion 124 of the plate 114 is apertured to receive attaching lugs, such as 126, of suitably shaped receptacles 128 for receiving and positioning in the drawer articles such as a lipstick and containers of mascara, rouge and eye shadow.

A portion of the drawer 20 between the plate 114 and an upstanding flange 130 formed at the rear of the stamping 18 provides a receptacle for receiving a box of cleansing tissue or the like 132, Fig. 2. A handle 134 for manipulating the drawer 20 may be secured to the face plate 108.

Mirror panels 136 may be cemented or otherwise fused to the external surface of each wall 75

5 of the cabinet with the exception of the bottom wall 4, and to the front plate or panel 108 of the drawer 20. Any of these panels or walls of the cabinet may therefore be used as a diffusely illuminated mirror if desired. The under surface of the lid 36, being chromium plated, may also be used as a diffusely illuminated mirror if desired.

10 The rim of the reflector 42 is rolled or reversely bent over the edge of the front mirror panel 136 about the reflector receiving opening in the plate 12 so as to present a finished appearance and to support the reflector in proper position.

15 Means are provided for controlling the energization of the luminous means 58 in response to the opening and closing of the drawer 20. This means comprises a switch 138 having a pair of fixed contacts or terminals 140 carried by an insulating plate 142 and a resilient contact or bridging member 144 also carried by the insulating plate. The insulating plate 142 is supported by a generally U shaped strap 146 fastened to the bottom plate 4 of the cabinet and between the side walls 24 and 26 of the drawer 20. The plate 142 is secured to the strap 146 by a lug 148 extending through a suitable slot in the forward end of said strap and by inturned lugs 150 struck out from the strap 146. The switch operating member 152 comprises a strip of sheet metal overlying the insulating plate 142, having an end portion or lug 154 loosely received in a suitable slot in the strap 146 and a down-turned end portion 156 slidably received in and guided by a suitable slot 158 in the insulating plate 142. The outer edges of the strip 152 may be enlarged as at 160 to limit the upward movement of the operating member 152 and to prevent detachment from the switch. An insulating piece or block 162 is slidably received in a suitable opening in the insulating plate 142 and connects the operating member 152 to the spring contacts 144. One of the contacts 140 is connected to one of the terminals of the lamp socket 56; the other contact and the other terminal of the lamp socket 56 are connected to the electrical source.

45 It will be apparent from the foregoing description that applicant has provided a combined cosmetic cabinet and illuminated mirror which is relatively simple and inexpensive from the manufacturing standpoint, compact, rugged and durable in construction and pleasing in appearance; wherein the cabinet has an article receiving drawer, an internal article receiving shelf and a lid overlying said shelf, in which means are provided for manipulating the shelf and lid in response to the opening of the drawer to project the articles on the shelf at least partially beyond the walls of the cabinet so that they may be placed in a position readily available for use or removal and replacement; and wherein the 50 cabinet is provided with an article receiving drawer arranged to control the energization of the means employed for illuminating the mirror.

55 Changes may be made in the form, construction and arrangement of the parts without departing from the spirit of the invention or sacrificing any of its advantages, and the right is hereby reserved to make all such changes as fairly fall within the scope of the following claims.

60 The invention is hereby claimed as follows:

70 1. In combination, a cabinet adapted to receive cosmetics or the like, a mirror, means for supporting said mirror upon a wall of said cabinet, luminous means behind said mirror, and means for directing light rays from said luminous means 75 about the periphery of said mirror whereby to

form an image in said mirror by light rays reflected from an object in front of the mirror.

2. In combination, a cabinet having a drawer adapted to receive cosmetics or the like and shiftable between opened and closed positions, a mirror, means for supporting said mirror upon a wall of said cabinet, luminous means within said cabinet behind said mirror, means for directing light rays from said luminous means about the periphery of said mirror whereby to illuminate an object in front of the mirror, and means operable in response to the shifting of said drawer for controlling said luminous means.

10 3. In combination, a cabinet having a shelf adapted to receive and support cosmetics or the like, said shelf being shiftable within the cabinet to and from a position wherein the articles are readily available for use, a mirror, means for supporting said mirror upon said cabinet, luminous means behind said mirror, means for directing light rays from said luminous means about the periphery of said mirror, and means for simultaneously shifting said shelf and operatively controlling said luminous means.

15 4. In combination, a cabinet having a shelf adapted to receive and support cosmetics or the like, said shelf being shiftable within the cabinet to and from a position wherein the articles are readily available for use, shiftable closure means for said cabinet in the path of movement of said shelf, a mirror, means for supporting said mirror upon said cabinet, luminous means behind said mirror, means for directing light rays from said luminous means about the periphery of said mirror, and means for simultaneously shifting 20 said shelf and said closure means.

25 5. In combination, a cabinet, one well of the cabinet having an opening therein, a mirror, luminous means within said cabinet and behind said opening, a semiconoidal reflector for said luminous means mounted within said opening, and a mirror partially covering said reflector to form an annular light transmitting opening about said mirror, thereby permitting illumination of 30 an object in front of the mirror.

35 6. In combination, a cabinet adapted to receive cosmetics or the like, said cabinet having an inclined face panel with an opening therein, a mirror within said opening and in the plane of said face panel, luminous means within said cabinet behind said opening, and a semiconoidal reflector for said luminous means mounted within said cabinet in a position to be partially covered by said mirror thereby to form an annular light transmitting opening about the mirror to permit illumination of an object in front of the 40 mirror.

45 7. In combination, a cabinet, one wall of the cabinet having an opening therein, a mirror, luminous means within said cabinet and behind said opening, a semiconoidal reflector for said luminous means mounted within said opening, a mirror partially covering said reflector to form an annular light transmitting opening about said mirror thereby permitting illumination of an 50 object in front of the mirror, and a mirror panel secured to and covering said wall of the cabinet about said opening.

55 8. A cabinet adapted to receive cosmetics or the like comprising a shell forming a cabinet 70 supporting bottom wall, side walls and an inclined front wall, and wall covering mirror panels secured in overlying contacting relation to said side and front walls.

60 9. A cabinet adapted to receive cosmetics or 75

- the like comprising a shell forming a cabinet supporting bottom wall, a top wall, side walls and an inclined front wall, and wall covering mirror panels secured in overlying contacting relation to said top, side and front walls.
10. A cabinet adapted to receive cosmetics or the like comprising a shell forming a cabinet supporting bottom wall and integral side walls, said side walls having an inclined forward edge,
- 10 15. A face plate secured to the shell and extending between the inclined forward edges of the side walls, a rear plate secured to the shell and extending between said side walls, and mirror panels secured to and covering the side walls, the face plate and said rear plate.
11. A cabinet adapted to receive cosmetics or the like comprising a sheet metal stamping forming a cabinet supporting bottom wall and integral side walls, said side walls each having an inclined forward edge, a sheet metal face plate secured to and extending between said side walls at the inclined forward edges thereof, a sheet metal rear plate secured to the side walls and extending between the rear edges of said walls, and mirror panels cemented to the side walls, the face plate and the rear plate.
12. A cabinet adapted to receive cosmetics or the like, comprising a shell forming a cabinet supporting bottom wall, side walls and an inclined front wall, mirror panels secured in contacting relation to and overlying said side and front walls, said front wall and the mirror panel secured thereto having an opening therein, a reflector within said opening and extending into said cabinet, said reflector having a reversely turned rim overlying the edge of said opening, a mirror detachably mounted on said reflector and partially covering said reflector to form an annular light transmitting opening about said mirror, luminous means within said reflector behind said mirror, and a drawer shiftably mounted in said shell beneath the inclined front wall.
13. A cabinet adapted to receive cosmetics or the like, comprising a shell forming a cabinet supporting bottom wall, side walls and an inclined front wall, mirror panels secured in contacting relation to and overlying said side and front walls, said front wall and the mirror panel secured thereto having an opening therein, a reflector within said opening and extending into said cabinet, said reflector having a reversely turned rim overlying the edge of said opening, a mirror detachably mounted on said reflector and partially covering said reflector to form an annular light transmitting opening about said mirror, luminous means within said reflector behind said mirror, and a shelf shiftably mounted in said cabinet to and from a position wherein articles carried by said shelf are projected beyond the top of said cabinet.
14. A cabinet adapted to receive cosmetics or the like, comprising a shell forming a cabinet supporting bottom wall, side walls and an inclined front wall, mirror panels secured in contacting relation to and overlying said side and
